UNITED STATES PATENT OFFICE.

FREDERICK H. BEMIS, OF BINGHAM CANYON, UTAH, ASSIGNOR OF TWO-THIRDS TO ENOS A. WALL AND GEORGE L. BEMIS, OF SALT LAKE CITY, UTAH.

SEPARATOR.

SPECIFICATION forming part of Letters Patent No. 772,860, dated October 18, 1904.

Application filed September 9, 1903. Serial No. 172,499. (No model.)

To all whom it may concern:

Be it known that I, FREDERICK H. BEMIS, a citizen of the United States, residing at Bingham Canyon, in the county of Salt Lake and State of Utah, have invented certain new and useful Improvements in Separators, of which the following is a specification.

My invention relates to that class of separators in which a plurality of inclined screens of different mesh are mounted in a vertically and bodily movable frame, which frame is retracted against the action of a spring and then suddenly released and thrown into contact with a bumper. In such prior separator the cam, spring, and bumper were located at about the middle of the screen-frame and the frame was carried by two pairs of links for bodily movement.

The object of my invention is to improve such prior construction by having the screen-frame extended upwardly at an incline from its lower pivoted end and to provide a cam engaging the higher end of the screen-frame to depress it against the action of a spring and suddenly release it, so that the high end of the frame, which is the end at which the ore is fed, and therefore the heavier, will fly up against a bumper with sufficient force to cause the ore particles to be thrown upwardly out of interstices of the screens, and so clear them at every stroke. Furthermore, in throwing the ore upwardly it will be on a line perpendicular to the inclined surfaces of the screens and not at an angle thereto, as in said prior construction, and so in its return movement the ore will fall upon the screens a short distance nearer the discharge ends thereof and the oversize particles for every screen will thus be moved toward the discharge end thereof and be discharged into suitable receptacles. Thus all clogging of the screens by the usually moist ores will be prevented.

A further object of the invention is to provide a screen-frame which shall be adjustable at its pivoted end, so that its inclination and the inclination of the series of screens may be changed at pleasure.

These objects I accomplish by the mechan-

ism shown in the accompanying drawings, in which—

Figure 1 is a sectional side elevation of my improved separator. Fig. 2 is a front end elevation, and Fig. 3 is a perspective of one of the screens.

A indicates the stationary bed, at the front or head end of which the parallel uprights A' A' are secured. The upper ends of the uprights A' A' are connected by the buffer-forming cross-bar A², which is connected to the base A by the long bolts A³ A³, so that an absolutely rigid construction capable of resisting the necessary jarring of the screen-frame B is afforded.

The rear or tail end of the base is provided with short uprights A⁴ A⁴, which are connected at their upper ends to the top cross-piece A² by the inclined braces A⁵. The inclined screen-carrying frame B comprises a bottom or main portion B', pivoted at its lower end on a rod b, mounted in any of a series of apertures b² in the uprights A⁴, and the higher or head end of the screen-frame rests upon a spiral spring C, mounted upon a rod C', secured to the base A and provided with a nut c at the lower end of the spring, so that by adjusting the nut the tension of the spring may be adjusted in order that the spring may throw the screen-frame upwardly against the bar A² with any desired degree of force.

The upper half of the screen-frame B is provided with a suitable housing or boxing B² to receive the individual screens B³, which, as usual, vary in mesh, the coarsest being at the top and the finest at the bottom, all the screens being inclined parallel to the screen-frame B. These individual screens rest one upon the other or may be inserted in the commonly-employed slideways, as may be desired, and their lower ends discharge the material too coarse to pass through them upon the chutes b³ b⁴ b⁵ b⁶, from which the material is conducted in the usual manner to suitable receptacles. The material falling through the lowest screen passes to a suitable receptacle. (Not shown.)

D indicates a shaft mounted in front of the

top frame-bar A² and provided with a drive-pulley d and a suitable cam or tappet d', with the arms of which engage a projection B⁴ at the upper forward portion of the screen-frame, so that as the cam is rotated it will depress the high end of the screen-frame B and suddenly release it, whereupon the spring C will throw the screen-frame upwardly against the buffer-bar A². This action will cause the material to be thrown upwardly to clear the screens of all material sticking in their meshes, and the coarser material will also be thrown upward on a line perpendicular to the inclined faces of the screens and not at an angle therefore, as would be the case were the screen-frame not pivoted at one end and receiving its bumping action at its middle. It will be seen, therefore, that the material will not fall upon the same spot from which it was projected, but it will fall slightly to the rear or toward the discharge ends, and so the escape of the coarser material from the several screens will be greatly facilitated and not depend on the incline of the screens alone. This is very important where the material being separated contains flat-sided particles of crushed rock, &c. The bumping action takes place at the high end, which gives the length of the stroke at that end twice what it is at the lower end of the screens and of course a diminishing length of throw from the head or high end down, and this is very important for the reason that the screens are always more heavily loaded at their upper ends, and therefore require at such point a more violent agitation.

E indicates the feed-hopper, which is mounted on top of the fixed framework and discharges upon the higher end of the top screen or sieve B³.

40 What I claim is—

1. A separator comprising, an inclined spring-supported screen-carrying frame pivoted at its lower or tail end in fixed bearings, means for depressing and suddenly releasing said frame, and a rigidly-secured bumper or contact-piece at the head end to check the upward throw thereof.

2. A separator comprising, a main frame, an inclined spring-supported screen-carrying frame pivoted adjustably at its lower or tail end in fixed bearings to vary its inclination, means for depressing and suddenly releasing the screen-carrying frame and a rigidly-secured bumper or contact-piece at the head end to check the throw thereof.

3. A separator comprising a main frame, an inclined spring-supported spring-carrying

frame pivoted at its lower or tail end in fixed bearings and provided at its upper or head portion with a housing and chutes, a plurality of graded screens in said housing and parallel with the inclined frame, means for depressing and suddenly releasing the screen-carrying frame, and a rigidly-secured buffer or contact-piece on the main frame at the head end of the screen-carrying frame to check the upward throw thereof.

4. A separator comprising, a main frame, an inclined screen-carrying frame pivoted at its lower or tail end in fixed bearings, a spring under the head end thereof, means for regulating the tension of the spring, a rotary cam over the head end of the screen-carrying frame and adapted to engage the same, depress it against the action of the spring and suddenly release it, and a rigidly-secured buffer on the main frame at the head of the screen-carrying frame to check the upward throw thereof.

5. A separator comprising a main frame having rear uprights provided with a plurality of apertures, a rod adjustable to different heights by means of said apertures, an inclined screen-carrying frame pivoted at its rear lower tail end on said rod, a spiral spring supporting the upper or head end of the screen-carrying frame, a rod extending through said spring, a nut on the rod to regulate the tension of the spring, a rotary cam on the upper forward end of the main frame and engaging the upper or head end of the screen-carrying frame to depress and suddenly release it and a buffer on the main frame to check the upward throw of the screen-carrying frame.

6. A separator comprising, an inclined, spring-supported screen-carrying frame pivoted at its lower or tail end in fixed bearings and having a housing at its upper or head portion, a series of screens of graded mesh mounted removably one above the other in said housing, chutes on the housing at the lower rear discharge ends of said screens, a rotary cam for depressing the screen-carrying frame and suddenly releasing it, and a rigidly-secured bumper in the upward path of the head end of the screen-carrying frame to receive the impact thereof.

In testimony whereof I affix my signature in presence of two witnesses.

FREDERICK H. BEMIS.
